S. P. BURDICK, OF NEW YORK, N. Y.

Letters Patent No. 77,955, dated May 19, 1868.

IMPROVEMENT IN BUCKLES.

The Schedule referred to in these Letters Patent and making part of the same.

TO ALL WHOM IT MAY CONCERN:

Be it known that I, S. P. BURDICK, of the city, county, and State of New York, have invented a new and useful Improvement in Buckles; and I do hereby declare the following to be a full, clear, and exact description thereof, which will enable those skilled in the art to make and use the same, reference being had to the accompanying drawing, forming part of this specification, in which drawing—

Figure 1 represents a longitudinal section of this invention.

Figure 2 is a front view thereof.

Figure 3 is an inverted plan thereof.

Figure 4 is a rear view thereof.

Figure 5 is a similar view with the cross slide.

Similar letters indicate corresponding parts.

This invention relates to a buckle, which is provided with a cam extending clear across the width of the belt, and secured to an axle, one end of which forms a lever, in combination with a stop and catch formed by projections on the edge of the shell or body of the buckle, in such a manner that when the belt has been passed through the buckle it is fastened by depressing the lever between the stop and catch, and said belt can thus be fastened at any desired point, no holes being required to receive the tongue of the buckle.

The cam-shaft is also provided with a lip at the end opposite the lever, said lip being made to catch over the edge of the shell, and preventing the cam-shaft from being forced out toward the stop and catch.

The front end of the shell of the buckle is provided with a flange projecting downward, and cut out in the middle, in such a manner, that by the cavity in the flange, the end of the belt is brought in a central position, and by the flange itself said end is depressed and prevented from sticking up.

A represents the shell or body of my buckle, which is made of sheet metal or any other suitable material, and which forms the bearings for the shaft a. This shaft is provided with a cam, a', which extends clear across the width of the shell, and at one end of said shaft a lever, b, is formed, while its opposite end forms a lip, c, as clearly shown in fig. 3 of the drawing.

The lever b works close to one side of the shell, and on this side is formed a catch, d, and a stop, e. When the lever is depressed it drops over the catch with a snap, and then it bears up against the stop e, so that it is retained, and prevented from moving spontaneously in either direction.

The lip c catches over the opposite edge of the shell, and prevents the shaft being forced out in a longitudinal direction by the action of the lever b and catch d.

The shell A may be strengthened by lugs or ears, f, (see fig. 3,) which project under the shaft a and cam a', and enable said cam to take a firm hold of the belt or other article passing through the buckle.

The front end of the shell A is provided with a flange, g, which projects downward, and which is hollowed out in the middle, (see fig. 2,) so that when a belt is passed through the buckle, the end thereof, on striking the concave part of the flange g, is conducted to the centre of the shell, and by the flange itself the end of the belt is depressed, as shown in fig. 1, it being very awkward in some cases if the end of the belt is permitted to stick up, which it would be liable to do without the flange.

When the belt has been passed through the shell to the required point, the lever b is turned until it strikes the stop e, and by this action the cam is brought to bear on the belt, and clamp the same firmly between its edge and the shell, and by means of the stop and the catch the lever and the cam are retained, so that the belt cannot be drawn through the shell in either direction until the cam is thrown off.

Where a cross-belt is used, or where the buckle is made adjustable on such a belt, a guide or loop, i, is attached to the under surface of the shell A, as shown in fig. 5.

Having thus described my invention, what I claim as new, and desire to secure by Letters Patent, is—

1. The lip e, turned up from the lower face of the shell A to hold the lever b, when the cam a' is fully locked and operating in combination with said cam, shell, and lever, and the lip c, as herein described.

2. The construction of the shell A of a flat plate, having a depressed concave flange, g, at its front edge, substantially as and for the purpose described.

3. The guide i, secured to the shell A, and running crosswise to the belt, which is secured in said shell, substantially as and for the purpose set forth.

Witnesses:

W. HAUFF,

E. F. KASTENHÜTER.
